UNITED STATES PATENT OFFICE

LEWICKI J. LEON, OF WEST CHICAGO, ILLINOIS, ASSIGNOR TO THE ANDREW B. HENDRYX COMPANY, OF NEW HAVEN, CONNECTICUT

BIRD CAGE BASE

Application filed May 2, 1929. Serial No. 359,871.

This invention relates to improvements in bases for bird cages.

One object of my invention is to provide a bird cage base and a sliding drawer there-with the base so designed that the drawer may have a diameter substantially equal to that of the base and thus permit the drawer when closed to completely fit the base and provide a vermin proof construction by reason of the fact that there are no spaces between the walls of the drawer and the base to allow seed, droppings or other refuse being displaced from the drawer and collecting in the base to foul the same as heretofore.

Another object of my invention is to provide a base construction wherein the upright marginal wall of the drawer when closed forms a portion of the upright marginal wall of the base, thereby allowing the base to be made in skeleton form and cheaper than heretofore.

A further object of my invention is to connect the skeleton members of the bottom together by means of straps which also serve as stops for the sliding drawer and also allow the drawer to have the largest possible diameter.

The invention consists further in the matter hereinafter described and claimed.

In the accompanying drawings—

Fig. 1 is a front elevation view of a bird cage having a base constructed in accordance with my invention;

Fig. 2 is a top plan view of the base with the drawer slid part way out of the same;

Fig. 3 is an enlarged vertical sectional view taken through the base on line 3—3 in Fig. 2 with the drawer completely closed in the base; and

Fig. 4 is a sectional view taken through the base and the drawer on line 4—4 of Fig. 2.

As shown in Fig. 1, the cage has an upright body 1 and a base 2, both in circular form. The body 1 is made of suitably spaced and connected wires and has a flat base ring 3 at its lower end, as shown in Figs. 2 and 3. The wires which form the cage body extend to this ring and are rigidly secured thereto.

Several of these wires as shown in Figs. 2 and 3, are indicated by 4, 4. The cage body 1 is releasably attached to the base 2 by a number of catch members 5, 5 arranged about the base 2 on its top wall 6 about the outside of the cage body 1. The base 2 has an annular recess 7 around its opening 8 to receive the base ring 3. The recess 7 has a depth equal to the thickness of the ring 3 so that the latter when seated in the recess will have its top surface substantially flush with the upper surface of the top wall 6 of the base 2 and thus permit the catches 5, which are pivoted on said top wall 6, to be swung over the ring between the wires 4, 4 to hold the ring in the recess and lock the base 2 and cage body 1 together.

In accordance with my invention the base 2 is made in skeleton form having an upper annular member 9 and a lower annular member 10. The members 9, 10 are vertically spaced apart and are connected together and held in that relation by a number of connectors 11, 11 which as shown in the drawings are in the form of straps arranged about the outside of the base and riveted or otherwise rigidly connected to the respective members 9, 10. The connectors 11, 11 are three in number and two of them are on opposite sides of the base and the third is at the rear side of the base, as shown in Fig. 2. This leaves open the space between the members 9, 10 at the front side of the base so that a drawer 12 may be slid into and out of the base between the members 9, 10 without hindrance by any of the connectors 11. The latter form stops for the drawer when it reaches fully closed position in the base.

The connectors 11, 11 at the sides of the base are diametrically disposed and being on the outside of the base permit the drawer 12 to be made with a diameter equal to the largest diameter of the base as measured between the inner sides of said connectors. With the members 9, 10 of the base spaced apart, the surrounding upright marginal wall 13 of the drawer may fit in this space and close the same when the drawer is in fully closed position in the base, as shown in Fig. 3. The height of the wall 13 is such

that it closes this space when the drawer is closed and said wall has a flange 14 which extends inward beneath and substantially in contact with the adjacent lower edge of 5 the upper member 9.

The bottom wall 15 of the drawer rests on the upper edge of the lower member 10 of the base 2 when the drawer is closed in the base and also as the drawer is slid into and 10 out of the base. As an additional support for the drawer, I provide an upright member 16 in the base on the lower member 10 thereof. The support 16 is in the form of a strip extending diametrically across the 15 member 10 beneath the drawer from the front to the rear side of the base, as shown in Figs. 2 and 3. Said strip is high enough for the under side of the bottom wall 15 of the drawer to rest and slide on the upper 20 edge of the strip. The bottom wall 15 of the drawer has depending portions 17, 17 fitting on opposite sides of the strip to guide the drawer in its sliding movement into and out of the base 2. The guides 17, 17 may be 25 made by striking down portions of the bottom wall 15 on opposite sides of the strip as shown in Figs. 2 and 4. The strip 16 has a flange 18 along its lower edge by which the strip is secured to the bottom wall 19 of the 30 lower member 10.

The drawer 12 is provided on its front side with a knob 20 by means of which the drawer may be readily grasped for sliding it into and out of the base. The opposed 35 edges of the members 9, 10 may be beaded, as at 21, 21 to strengthen them and also provide a finish therefor, as the beads are on the outer side of the base. The bead 21 on the lower member 10 also provides a rounded 40 bearing surface for the bottom wall of the drawer and thus presents no sharp edges to cut or scratch the drawer as would be the case should a blunt edge be employed.

With the beads 21 on the outer side of the 45 base, the connectors 11, 11 are bent outward to extend about them, as shown in Fig. 3. This allows the drawer 12 to have the largest possible diameter without restriction by either of the upper or lower members 9, 10 50 of the base. This is one of the important features of my invention because the drawer when closed in the base has its bottom wall 15 completely covering the lower member 10 and prevents seed, refuse or other droppings 55 from entering and collecting in the same to foul the base, as in structures heretofore employed.

Another important feature of my invention resides in the fact that the surrounding 60 upright marginal wall 13 of the drawer forms a closure for the space between the members 9, 10 when the drawer is closed in the base. This permits making the base 2 in skeleton form because the marginal wall 13 of the 65 drawer forms a finishing wall for the base

between its members 9, 10. Making the base in this way reduces its cost of construction because of the complete elimination of a connecting wall between the upper and lower members of the base as heretofore employed. 70 With the marginal wall 13 of the base forming a finishing wall for the base, the drawer serves a dual purpose, thereby contributing to a reduction in cost of the manufacture of both the drawer and the base. 75

In addition to cheapening the cost of the construction, the arrangement described also allows the use of contrasting colors on the skeleton part of the base and the drawer. By 80 painting the drawer 12 a light color and the upper and lower portions 9, 10 a darker color, the upright marginal wall 13 of the drawer which is exposed in the space in the base will give the effect of a strip band completely 85 encircling the base. This is very attractive and permits a combination of colors to be used in a drawer type of base.

The drawer 12 is provided on its front side with a strap 22 to which the knob 20 is secured. The strap 22 extends above and below the drawer and provides stops which contact against the outer sides of the upper and lower members 9, 10 of the base to limit the inward movement which may be given to the drawer. The strap 22 is preferably given the 90 same shape and ornamentation as the straps 11, 11 so as to be in harmony with the entire design of the base.

The details of structure and arrangement of parts may be variously changed and modified without departing from the spirit and scope of my invention. 100

I claim as my invention:

1. A bird cage base comprising upper and lower members vertically spaced apart, means for securing said members together, and a drawer slidably mounted in the base through the space between said members, said drawer having an upright surrounding marginal wall to close said space when the drawer is closed. 105

2. A bird cage comprising upper and lower members vertically spaced apart, a drawer slidably mounted in the base through the space between said members, said drawer having a surrounding marginal wall to close said space when the drawer is closed, and straps connecting the members together and providing stops for the drawer. 115

3. A bird cage comprising upper and lower members vertically spaced apart, a drawer slidably mounted in the base through the space between said members, said drawer having a surrounding marginal wall to close said space when the drawer is closed, straps connecting the members together across said space and providing stops for the drawer, and a stop carried by the drawer to contact with said members when the drawer is closed. 120

4. A bird cage base comprising connected 130

- together upper and lower members vertically spaced apart, a drawer slidably mounted in the base through the space between said members, said drawer having an upright surrounding marginal wall to close said space when the drawer is closed, and a support for the drawer on the lower member of the base. 5. A bird cage base comprising connected together upper and lower members vertically spaced apart, a drawer slidably mounted in the base through the space between said members, said drawer having an upright surrounding marginal wall to close said space when the drawer is closed, a support for the drawer on the lower member of the base, and means formed integrally with the drawer bottom to co-operate with said support to guide the drawer as it is slid into and out of the base. 10. A bird cage base, comprising a lower base portion having a marginal wall, straps secured to said wall and projecting vertically upward therefrom, an upper base portion also having a marginal wall and said wall being secured to the upper end of said straps, the walls of said upper and lower portion being held in spaced relation vertically by said straps, and a drawer slidably mounted between said portions and having an upright marginal wall closing the space between the walls of said upper and lower portions. 15. A bird cage base comprising connected together upper and lower members vertically spaced apart, a drawer slidably mounted in the base through the space between said members, said drawer having an upright surrounding marginal wall to close said space when the drawer is closed, an upright strip on the lower member of the base to support said drawer, and bosses pressed downward from the bottom portion of said drawer on opposite sides of said strip to guide the drawer in its sliding movement into and out of the base. 20. A bird cage base, comprising a lower base portion having a marginal wall provided with a bead at its upper edge, and an upper base portion having a marginal wall provided with a bead at its lower edge, vertically disposed straps secured to the marginal walls of said base portion and securing the portions together with said beads in spaced relation vertically, and a drawer slidably mounted between said beads. 25. A bird cage base, comprising a lower base portion having a marginal wall provided with a bead at its upper edge, and an upper base portion having a marginal wall provided with a bead at its lower edge, vertically disposed straps secured to the marginal walls of said base portion and securing the portions together with said beads in spaced relation vertically, and a drawer slidably mounted between said beads, and said drawer having an upright marginal wall closing the space between the beads. 30. A bird cage base, having a marginal wall comprising upper and lower separate wall sections secured together in superposed vertically spaced relation, and a movable wall portion between the fixed wall portions and closing the space therebetween, a drawer slidably mounted in the base and said movable wall portion constituting an upright marginal wall of the drawer. 35. A bird cage base, having its marginal wall comprising upper and lower wall portions, means for maintaining said wall portions in superposed relation and vertically spaced apart, said wall portions being comprised of continuous bands, and an intermediate wall portion also comprising a continuous band closing the space between said upper and lower wall portions, a drawer slidably mounted in said base and said intermediate wall portion constituting an upright marginal wall for said drawer. 40. A bird cage base, having its marginal wall comprising upper and lower wall portions in superposed relation and vertically spaced apart, said wall portions being comprised of continuous bands, and an intermediate wall portion also comprising a continuous band closing the space between said upper and lower wall portions, a drawer slidably mounted in said base and said intermediate wall portion constituting an upright marginal wall for said drawer, straps connecting the upper and lower wall portions 45. A bird cage base, having its marginal wall comprising upper and lower wall portions in superposed relation and vertically spaced apart, said wall portions being comprised of continuous bands, and an intermediate wall portion also comprising a continuous band closing the space between said upper and lower wall portions, a drawer slidably mounted in said base and said intermediate wall portion constituting an upright marginal wall for said drawer, straps connecting the upper and lower wall portions 50. A bird cage base, having its marginal wall comprising upper and lower wall portions in superposed relation and vertically spaced apart, said wall portions being comprised of continuous bands, and an intermediate wall portion also comprising a continuous band closing the space between said upper and lower wall portions, a drawer slidably mounted in said base and said intermediate wall portion constituting an upright marginal wall for said drawer, straps connecting the upper and lower wall portions 55. A bird cage base, having its marginal wall comprising upper and lower wall portions in superposed relation and vertically spaced apart, said wall portions being comprised of continuous bands, and an intermediate wall portion also comprising a continuous band closing the space between said upper and lower wall portions, a drawer slidably mounted in said base and said intermediate wall portion constituting an upright marginal wall for said drawer, straps connecting the upper and lower wall portions 60. A bird cage base, having its marginal wall comprising upper and lower wall portions in superposed relation and vertically spaced apart, said wall portions being comprised of continuous bands, and an intermediate wall portion also comprising a continuous band closing the space between said upper and lower wall portions, a drawer slidably mounted in said base and said intermediate wall portion constituting an upright marginal wall for said drawer, straps connecting the upper and lower wall portions 65. A bird cage base, having its marginal wall comprising upper and lower wall portions in superposed relation and vertically spaced apart, said wall portions being comprised of continuous bands, and an intermediate wall portion also comprising a continuous band closing the space between said upper and lower wall portions, a drawer slidably mounted in said base and said intermediate wall portion constituting an upright marginal wall for said drawer, straps connecting the upper and lower wall portions

In testimony whereof I affix my signature.

LEWICKI J. LEON.
